S. E. PURDUM

POCKET KNIFE AND SAVINGS BANK

Filed Jan. 14, 1925

UNITED STATES PATENT OFFICE.

SAMUEL E. PURDUM, OF MACOMB, ILLINOIS.

POCKETKNIFE AND SAVINGS BANK.

Application filed January 14, 1925. Serial No. 2,462.

The present invention relates to a combined pocket knife and savings bank, the primary object of the invention being to provide a knife having a hollow handle providing compartments for the reception of coins.

An object of the invention is to provide means to lock the compartment so that unauthorized persons may not remove the coins therefrom.

10 A still further object of the invention is the provision of a guard disposed adjacent to the slot through which coins are inserted to prevent the coins from being removed by gravity, through the slot.

15 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

25 Referring to the drawing:

Figure 1 is a side elevational view of a combined knife and bank constructed in accordance with the invention.

Figure 2 is a longitudinal sectional view 30 through one of the coin compartments.

Figure 3 is a view illustrating one of the side compartments as removed, showing the manner of inserting the key.

Figure 4 is a sectional view taken transversely through the device at a point substantially centrally thereof.

Figure 5 is a fragmental sectional view taken at right angles to Figure 2 and illustrating the key as operating to unlock the coin compartment.

Figure 6 is an elevational view of the knife, one of the coin compartments being shown in section.

Figure 7 is a perspective view of one of the removable end members of a coin compartment.

Referring to the drawing in detail, the reference character 5 indicates the body portion of the combined knife and bank which comprises sections 6 and 7 respectively, which sections are secured in spaced relation with each other by means of the pins 8 that also act as bearings for the knife blades 9 that are mounted therebetween.

55 Each of the sections 6 embodies an inner wall 10 and an outer wall 11 which walls

are held in spaced relation with each other by means of the flange 12 forming a part of one of the walls, the flange 12 extending around one end of each section to close one end thereof.

Each section has one of its ends partially closed as by means of a removable end piece 15 which is shown as spaced from one wall of the section providing a clearance or opening 26 through which a coin such as indicated at 27 may be inserted, the coin being forced over the fingers 21 of the end piece to be hereinafter more fully described.

These end pieces are identical, and as shown, embody a plate 16 formed with cut out portions defining spaced fingers 17. Secured to the plate 16 by means of the rivets 18 is a spring plate 19 constructed to provide fingers 20 that are curved downwardly as at 21 to frictionally engage one wall of the compartment of which the end member forms a part.

Disposed between the fingers 20 is a locking tongue 22 that is of a length greater than the fingers 20, and as shown, is curved downwardly in a direction opposite to the curvature of the fingers 20, where the same is designed to pass into the opening 23 formed in one wall of the coin compartment to the end that when the end member is slid into position, the locking tongue 22, by its engagement within the opening 23, will lock the end member against movement.

The opening 23 is provided with an offset portion 24 that provides a clearance for the key to permit the key to pass through the opening while it is being operated to release the end member.

The key is indicated by the reference character 25 and is adapted to be inserted in the space between the sections, when the blades have been moved to their open positions, with the result that as the key contacts with the locking finger 22 of the end member which is being removed, the locking finger will be forced from its position within the opening 23 to the end that the end member will be forced outwardly disengaging the walls of the coin compartment.

Thus it will be seen that when the end member has been removed, the coins contained within the coin compartment will fall therefrom.

When the end member is again positioned to close the end of the coin compartments, it is obvious that the locking tongue will

automatically position itself within the opening 23 to lock the end member against movement.

It might be further stated that the flange 12 is cut away to provide an opening 13 through which a key may be inserted to engage a coin held between the fingers 21 and one wall of the section in which the coin is positioned, to force the coin from the device, should it be desired to insert the key to remove the end piece 15. A guarding flange 14 extends inwardly adjacent to the opening to prevent coins from being removed by gravity or by shaking the body portion.

From the foregoing it will be obvious that coins may be inserted in the sections between the end sections and the outer walls 11 of the lateral sections of the body portion, the coins being forced over the fingers 21 that guard against coins being removed through this opening.

I claim:

In a device of the character described, a body portion embodying a substantially narrow compartment, one wall of the compartment

having a key opening, one end of the body portion adjacent to the opening being open, a removable closure for closing the open end of the compartment, said removable closure being of a width to provide a lateral passageway to permit coins to be positioned in the compartment, said closure including a locking finger extended in one direction and adapted to position itself in the key opening to lock the closure in position, fingers forming a part of the closure and curved in the opposite direction from the locking finger, the last mentioned fingers adapted to frictionally engage one wall of the compartment to urge the locking finger within the key opening, said last mentioned fingers adapted to prevent coins from passing out of the lateral passageway, and said locking finger adapted to be forced from the key opening to permit the closure to be removed.

In testimony that I claim the foregoing as my own, I have hereto affixed my signature.

SAMUEL E. PURDUM.
